KNEE BRACE

Augustus K. Snyder, Annapolis, Md.

Application January 22, 1938, Serial No. 186,327

1 Claim. (Cl. 128—88)

(Granted under the act of March 3, 1883, as
amended April 30, 1928; 370 O. G. 757)

This invention relates to a knee brace particularly designed for users participating in athletics.

A primary object of this invention resides in the provision of a knee brace which will preclude the possibility of injury to a user and will especially prevent further injury to a knee joint previously injured in the absence of this invention.

A still further object of this invention resides in the provision of a knee brace which is so designed as to be of durable and strong construction and at the same time of minimum weight and bulk, thus affording the user ample support and protection with the least possible encumbrance.

15 A very important object of this invention is that it will intercept and counteract forces directed toward the knee, and in so doing will partly absorb the shock caused by such impacting forces and will transmit the remaining major portion 20 of the shock to the fleshy parts of the calf and thigh.

A still further object of this invention is the bracing of the previously injured knee joint when the crucial, internal and lateral ligaments of the 25 knee have so stretched or damaged as to allow abnormal lateral and fore and aft motion, whereby this knee brace will protect the knee from further injury and allow continuance of activity while the knee joint is healing.

30 A still further object of this invention is that it is so designed as to permit the user safely to participate in games without injury to his opponent and not only without further aggravation of any injury previously inflicted upon the joint 35 but also permitting healing to take place while continuing to use the knee joint.

With the foregoing and other objects in view, the invention consists in the construction, combination and arrangement of parts hereinafter 40 described and illustrated in the drawing, in which,

Fig. 1 is an elevational view of the invention in operative position;

Fig. 2 is a perspective view of the framework or skeleton of the knee brace of this invention;

45 Fig. 3 is a sectional view on line 3—3 of Fig. 2; and

Fig. 4 is a fragmentary portion of a modification of this invention.

There is shown at 10 the knee brace of this invention as applied about the knee joint 11 of a user. This knee brace 10 has a framework or skeleton and includes two flattened vertical supporting shafts 12 and 13 which are journaled together by a rivet 14, permitting movement of the shafts 12 and 13 about such rivet 14 in a sub-

stantially vertical plane only, but preventing any lateral movement whatever between the shafts 12 and 13.

Rivet 14 includes a wear-reducing bushing 15 therein, the bushing 15 as well as the shafts 13 and 14 being of a hard, light metal, preferably a nickel alloy sometimes commercially known as Monel metal. Similar vertical shafts 16 and 17 are similarly journaled together by rivet 18, the shafts 16 and 17 being intended to lie along the inside of the thigh and calf of the leg of the user, while the shafts 12 and 13 lie along the outside of the thigh and calf of the user.

As will be observed, the shafts 12, 13, 16 and 17 are substantially flattened and are shaped to fit snugly against the sides of the thigh and calf. The upper shafts 12 and 16 are secured together in proper spaced relation by a flattened metal band 19 which passes around the back of the thigh closely adjacent the top of the shafts 12 and 16. A similar flattened band 20 is similarly secured to the shafts 13 and 17 closely adjacent to the upper ends of these shafts near the joint, and in use overlies the lower edge of the kneecap of the user. A second flat metal band 21 is secured to shafts 13 and 17 immediately below the band 20. This band 21 extends about the top or upper part of the calf of the user's leg. Each of the bands 19, 20 and 21, preferably of the same material as the shaft, have a curvature compared to the curvature of the parts of the leg to which they are adjacent so that they will make little, if any, contact therewith, and if any contact is made it will be a light contact made only when the leg has been bent to the extreme permitted position. While the shafts 12, 13, 16 and 17 have been described as extending substantially vertically, it will be understood that they will be curved and fitted so as to lie snugly along the sides of the leg above and below the knee joint 40 of the leg, while the rivets 14 and 15 are positioned so that the journaling of the shafts through the rivets 14 and 15 will coincide with the normal line of flexure of the knee so as to permit normal bending of the leg relative to the 45 thigh. Side motion of the leg relative to the thigh or any other motion except a normal rearward bending of the leg is prevented by the shafts upon their rivets.

In order to hold the shafts in proper position 50 relative to the sides of the thigh and the leg, boots 22 and 23 are fitted on the shafts and are of a shape and size to snugly fit about the thigh and the calf, being held in position thereon by a suitable lacing or securing means 24 and 25, 55

tongues 26 and 27 being provided beneath the lacing 24 and 25 so as to prevent chafing of the skin by the lacing. These boots 22 and 23 will be made of leather or other suitable natural or artificial composition serviceable for this purpose. In fitting the boots to the shafts they will preferably be placed on the inner sides of the shaft and held thereto by suitable securing means such as rivets 28, the outer sides of the shafts being covered by flaps 29 of material similar to the boot and sewed thereto. The metal bands 19, 20 and 21 will likewise be protected by a coating or ribbon of similar material, wound therearound as at 30, the purpose of the shaft coverings 29 and band coverings 30 being to prevent possible injury to opponents or to the other leg of the user.

In operation, the knee brace having been properly fitted to the user is held in position merely by fastening the lacing or securing means 24 and 25 with the line through the joining rivets 14 and 18 coinciding with the normal line of bending of the knee. After the boots are thus properly secured in position the user will find that he is permitted all normal forward and bending positions of his knee joint, permitting him to run, walk or kneel without hindrance. Sidewise or lateral motion of the leg relative to the thigh is absolutely prevented, due to the overlapping of the shafts about their joining rivets 30 and preventing the ligaments of the leg from giving sidewise. If the leg has been previously injured before this brace was applied, it will be found that any sidewise weakness of the leg is permitted to heal while continuing normal activity of the leg in a walking, kneeling or running position. The user may likewise fall or be thrown to the ground, even violently, without any sidewise movement of the leg relative to the thigh being permitted.

The normal knee will not permit any bending of the leg relative to the thigh further than a vertical position, and even in most types of knee joint injury no such further motion can take place in the usual knee joint. However, to insure against any straining of the knee joint that might tend to cause the leg to bend forwardly rather than rearwardly toward the thigh, vertical shaft 13', which is joined to the inner side of the outer

shaft 12, may be provided with an upwardly extending lip which is folded over as at 32, and provides a stop member abutting against the lower forward edge 33 of the shaft 12 to prevent any possibility of the leg tending to bend forwardly beyond the normal permitted position, this stop flange 32 being likewise included on the other pair of the vertical shafts. Any other suitable means of preventing forward bending may be substituted.

Other modifications and changes in the proportions and arrangements of the parts may be made by those skilled in the art without departing from the nature of the invention, within the scope of what is hereinafter claimed.

The invention described herein may be manufactured and used by or for the Government of the United States of America for governmental purposes without the payment of any royalties thereon or therefor.

Having thus set forth and disclosed the nature of this invention, what is claimed is:

A knee brace comprising a thigh-embracing boot and a calf-embracing boot and articulated means connecting said thigh-embracing boot and said calf-embracing boot for flexure in a single plane only, said plane being the normal flexure plane of the knee, a rigid skeleton forming part of said calf-embracing boot, a rigid skeleton forming part of said thigh-embracing boot, said thigh boot skeleton comprising a pair of rigid bars extending vertically on opposite sides of the thigh and a semi-circular rigid band extending behind the thigh and holding said rigid bars in proper spaced relation, said calf boot skeleton comprising a pair of rigid bars extending vertically on opposite sides of the calf, a semi-circular rigid band extending behind the calf and a second semi-circular rigid band extending just below and forward of the kneecap to hold said calf boot bars in proper spaced rigid relation, said semi-circular bands about the front and back of the calf bracing the knee against sliding forward in its socket, said forward semi-circular rigid band acting as a knee protecting bumper in kneeling position.

AUGUSTUS K. SNYDER.
